UNITED STATES PATENT OFFICE.

SILAS C. MACDONNEY, OF CHICAGO, ILLINOIS.

CORNER-POST JOINT FOR PLATE-GLASSES.

1,083,502.

Specification of Letters Patent.

Patented Jan. 6, 1914.

Application filed February 5, 1913. Serial No. 746,413.

To all whom it may concern:

Be it known that I, SILAS C. MACDONNEY, a citizen of the United States, residing at Chicago, in the county of Cook and State of Illinois, have invented a new and useful Corner-Post Joint for Plate-Glasses; and I do hereby declare the following to be a full, clear, and exact description of the invention, such as will enable others skilled in the art to which it appertains to make and use the same.

This invention relates to a new and useful corner post joint between two pieces of plate glass.

15 As one of the objects of the invention, it is the aim to provide a joint of this nature, whereby the two pieces of plate glass may be held at various angles relative to one another, or alined.

20 Another object of the invention is to provide a corner post joint construction consisting of an outer post member and an inner post member comprising a series of trough-shaped bars arching one another telescopically, between which trough bars and the outer post member, the adjacent edges of two pieces of plate glass are adapted to be clamped.

Another object of the invention is the provision of adjustable connections between the outer post member and the inner post member, whereby the series of said trough-shaped bars may be adjusted relative to one another.

25 In practical fields it may be found necessary to subject the various features of construction of the joint to alterations, to which the patentee is entitled, provided the alterations fall within the scope of what is claimed.

40 The invention comprises further features and combination of parts, as hereinafter set forth, shown in the drawings and claimed.

In the drawings:—Figure 1 is a transverse sectional view of the improved corner post joint, showing the two pieces of plate glass arranged in alinement. Fig. 2 is a detail perspective view of one of the inner clamping trough-shaped bars shown in Fig. 1. Fig. 3 is a detail perspective view of

50 another of said trough-shaped bars shown in Fig. 1. Fig. 4 is a detail view of one of the clamping bars upon the outside, and that is adapted to be swung adjustably. Fig. 5 is a detail view of the outer post member. Fig. 6 is a transverse sectional view of a corner post joint, showing a slightly modi-

ed construction, and the two pieces of glass, held at 90 degrees or at right angles, the apex of which extends outwardly. Fig. 7 is a detail perspective view of one of the 60 trough-shaped post members shown in Fig. 6. Fig. 8 is a detail perspective view of another of said trough-shaped post members shown in Fig. 6. Fig. 9 is a detail transverse sectional view of a corner post construction partly broken away, showing a slightly modified structure. Fig. 10 is a transverse sectional view of a corner post construction, showing the two pieces of plate glass held at 90 degrees or at right angles 70 to one another, but just the reverse to that shown in Fig. 6; in other words, the two pieces of plate glass extend inwardly to substantially an apex. Fig. 11 is a detail view of the inner clamping trough-shaped bar. 75 Fig. 12 is a detail view of the inner reinforcing clamping bar that telescopically arches the clamping bar shown in Fig. 11.

Referring more particularly to all the figures of the drawings, the outer corner post member or bar (the structure of which is common throughout the figures) comprises two sheet metal arched bars 2 and 3 fitting one another, as shown in Figs. 1, 6 and 10. The inner bar 3 has its flange portions 4 85 terminating in beads or rolls 5, about which the flange portions 6 of the outer bar or post 2 extend, thereby enlarging the circumference of the beads or rolls 5. The inner sheet metal bar 3 is offset from the 90 outer sheet metal bar 2, to receive the head 7 of the bolt or screw 8, the shank of which extends inwardly of the window. This outer post 1 extends vertically the full length of the adjacent edge portions 9 of the two 95 pieces of plate glass 10, and in constructing the joint, it is to be understood that a plurality of bolts is to be utilized, being placed at intervals of the joint construction.

The outer clamping plates 11 are substantially of the same construction in each of the Figs. 1, 6 and 10. These clamping plates or bars 11 comprise the substantially S-shaped portions 12 and the straight parts 13. The curved portions 14 of the S-shaped 105 portions engage the beads or rolls 5, and when constructing this type of joint, and adjusting the parts to their proper positions in order to hold the plate glasses at the desired angles, the plates or bars 11 are adapted to hinge upon the rolls or beads 5. 110

The corner joint construction includes an

inner trough-shaped bar 15, through the portion 16 of which the shank of the bolt or screw 8 extends, as shown in each of the Figs. 1, 6 and 10. The flanges or sides of the bar 15 terminate in rolls or beads 17, which are engaged by the curved parts 18 of the S-shaped portions of the plates or bars 11, thereby hingedly connecting the sides of the trough-shaped bar 15 to said plates 11. Threaded upon the shank of the bolt 8 is a nut 19, for holding the bar 15 in the desired adjustable position. Telescopically arching the bar 15 is a second trough-shaped bar 20, through the part 21 of which the bolt also extends. This bar 20 constitutes efficient means for reinforcing the bar 15. Telescopically arching the bar 20 is a third trough-shaped bar 22, the flanges of which terminate in bulged jaws or clamping members 23, which in Figs. 1 and 6 engage the inner surface of the two pieces of plate glass, to hold said pieces of glass closely against the straight parts 13 of the plates 11, thereby clamping the glass firmly in place. However, in Fig. 10 the bulged resilient clamping jaws engage the flange extensions 24 of the sides of the reinforcing bar 20. Telescopically arching the bar 22 is a fourth trough-shaped bar, which acts as means to reinforce the entire interior construction of the corner post structure. In other words, the bar 25 reinforces all the bars 15, 20 and 22 combined. This trough-shaped bar 25 is adapted to extend the full height of the window construction, and its upper and lower ends are provided with the lateral ears 26, whereby the bar 25 may be secured firmly in position, owing to the screws 27 passing through the ears into the floor and ceiling of the show window. In the drawings only the ears at the lower end of the bar 25 are illustrated. Threaded upon the bolt 8 is a nut 28 having a sleeve extension 29 entering the registered apertures 30 of the parts 31 of the bars 22 and 25. This nut 28 not only holds the resilient or yieldable bulged jaws 23 in contact with the glass, in order to hold the glass in position, but also holds the bar 25 in position. When the nut 19 is adjusted inwardly of the show window, and the bar 15 moved inwardly, the straight portions 13 of the plates 11 will be thrown outwardly, and subsequently it is necessary to screw the nut 28 farther on the bolt 8, in order to bring the jaws 23 in contact with the two pieces of plate glass, in order to hold the glass as shown in Fig. 1. In order to hold the two pieces of plate glass as shown in Fig. 6 or in Fig. 10, the reverse of this adjustment of the parts is necessary.

From the foregoing it is to be understood there has been provided a simple, novel and particularly desirable corner post construction for plate glass show windows, and one which has been found practical, inasmuch

as the various parts of the structure, may be adjusted, for holding the two pieces of plate glass at various angles, whether an acute angle or otherwise, or in alinement.

The invention having been set forth, what is claimed as new and useful is:—

1. In a show window corner post construction, an outer channeled post member, outer clamping members fulcrumed upon the sides of the channeled post, means for adjusting the outer clamping members to different angles, a member having clamping jaws for clamping two pieces of plate glass against the outer clamping member, and means for adjusting the member with the clamping jaws.

2. In a show window construction, two pieces of plate glass, on outer channeled post member, outer clamping members fulcrumed upon the sides of the channeled post, means for adjusting the outer clamping members to different angles including a trough-shaped bar connected to the outer clamping members, a second trough-shaped bar, the sides of which terminate in clamping jaws to hold the plate glass against the outer clamping members, and means for adjusting the second trough-shaped bar.

3. In a show window construction, two pieces of plate glass, an outer channeled post member, outer clamping members fulcrumed upon the sides of the channeled post, means for adjusting the outer clamping members to different angles including a trough-shaped bar connected to the outer clamping members, a second trough-shaped bar, the sides of which terminate in clamping jaws to hold the plate glass against the outer clamping members, and means for adjusting the second trough-shaped bar, and a third trough-shaped bar telescopically arching intermediate the first and second trough-shaped bars to reinforce the structure.

4. In a show window construction, two pieces of plate glass, an outer channeled post member, outer clamping members fulcrumed upon the sides of the channeled post, means for adjusting the outer clamping members to different angles including a trough-shaped bar connected to the outer clamping members, a second trough-shaped bar, the sides of which terminate in clamping jaws to hold the plate glass against the outer clamping members, and means for adjusting the second trough-shaped bar, and a third trough-shaped bar telescopically arching intermediate the first and second trough-shaped bars to reinforce the structure, and a support fixed to stationary means to hold and reinforce the entire structure.

5. In a show window construction, two pieces of plate glass, an outer channeled post member, outer clamping members fulcrumed upon the sides of the channeled post, means for adjusting the outer clamping

members to different angles including a trough-shaped bar connected to the outer clamping members, a second trough-shaped bar, the sides of which terminate in clamping jaws to hold the plate glass against the outer clamping members, and means for adjusting the second trough-shaped bar, and a third trough-shaped bar telescopically arching intermediate the first and second trough-shaped bars to reinforce the structure, and a support fixed to stationary means to hold and reinforce the entire structure, and means carried by the outer channeled bar on which the various inner bars and the adjustable means are mounted.

6. In a show window construction, an outer channeled post member, outer clamping members having substantially S-shaped portions fulcrumed upon the sides of the channeled member, an inner trough-shaped bar having hinged connections with said S-shaped portions, whereby upon the adjustment of said trough-shaped bar the clamping members may be arranged at different

angles, a projection extending inwardly 25 from the channeled post member extending through the trough-shaped bar, means on the projection to hold the trough-shaped bar in adjusted positions, a second trough-shaped member mounted on the projection 30 having its sides terminating in resilient clamping jaws adapted to engage and clamp plate glass against the outer clamping members, means on the projection to hold the second trough-shaped member in adjusted 35 positions, a third trough-shaped member arching telescopically intermediate the first two bars for reinforcing the structure, and a support fixedly connected to floor and ceiling of the show window for bracing the 40 structure.

In testimony whereof I have signed my name to this specification in the presence of two subscribing witnesses.

SILAS C. MACDOWNNEY.
